SHOE AND MEANS FOR DECORATING
SAME

Charles K. Morgan, San Diego, Calif.

Application May 15, 1936, Serial No. 79,958

7 Claims. (Cl. 36—54)

My invention relates to improvements in shoes and has its widest application to low cut shoes, such as the slipper type or sandals.

Shoes of the above types are quite commonly worn with sport or evening dresses and it is considered essential by most women that they have a pair of shoes of appropriate color to match the color of each dress in their wardrobe. To secure a matched pair of shoes for each dress usually 10 involves considerable expenditure of money.

It is the object of my invention to provide a construction of a shoe which can be made to harmonize in color with a plurality of dresses, and thus will require the purchase of only one 15 pair of shoes; to provide a removable top vamp section and front strap; and to provide a novel means for securing a top vamp section to the main vamp section.

Other objects and advantages of my invention 20 will appear from the following description.

In the drawings:

Fig. 1 is a perspective view of a sandal embodying my invention;

Fig. 2 is a view in perspective of the fore portion 25 of said shoe before applying the removable top vamp section;

Fig. 3 is a view in perspective of one form of the removable top vamp section;

Fig. 4 is a plan view of the fore part of said 30 shoe with the top vamp section in place;

Fig. 5 is a cross-section of the fore part of said shoe taken on the line 5—5 of Fig. 4;

Fig. 6 is a similar view taken on the line 6—6 of Fig. 4;

Fig. 7 is a modified form of my invention and shows the fore part of the shoe before the removable section is applied;

Fig. 8 is a perspective view of another form of removable top vamp section;

Fig. 9 shows the parts shown in Figs. 7 and 8 in assembled position;

Fig. 10 is a modified form of top vamp section shown in perspective; and

Fig. 11 shows the last-mentioned part in place 45 on a shoe similar to the form shown in Fig. 2.

The form of low cut shoe or sandal shown in Fig. 1 to illustrate my invention comprises the sole 11, the upper 12, the heel 13, the instep strap 14, and the main vamp section 15 which is secured in the usual manner to the sole 11. This vamp section may be perforated as shown, or it 50 may be imperforate as shown in Fig. 7.

The main vamp section 15 (see Fig. 2) is adapted 55 to be stamped or die cut from a single piece of material to provide the straps 16 which are

secured to the sole 11; and the series of transverse straps 17 which lie across the top of the vamp section. It is optional with the designer of the shoe whether the perforations 18 are provided as all that is needed for my invention is 5 some form of a plurality of straps 17 across the top of the vamp.

The removable top vamp section 20 (see Fig. 3) may be made in several different forms as shown 10 in Figs. 3, 8, and 10. Other variations are possible.

In general, this removable top vamp section 20 comprises the body portion 21, to the upper end of which it attached the front strap 22, which may or may not be formed of the same piece of 15 material. Near the bottom 25 or the top of the longitudinal recess cut in the body portion 21 I secure strips of material, usually identical in color with the material forming said body portion, which strips 23 and 24 are adapted to be interwoven in said recess with the series of transverse straps 17 of the vamp. By means of this interlacing of the strips 23 and 24, the body portion 21 is secured on top of the main vamp section 15 together with the front strap 22. 20 25

A single strip may be employed and still accomplish the results of my invention.

The main vamp section 15, and the upper section 12 are usually made of a material of neutral color which will harmonize readily with a 30 large number of colors. On the other hand the removable top vamp section 20 and front strap 22 with strips 23 and 24 are made of a material colored to match a dress of a particular color. In this way, by providing a plurality of removable top vamp sections of different colors, which are purchased with each pair of shoes, it is possible for a woman to match the shoes to the 35 dress she is wearing by attachment of a suitably colored top vamp section. Several of these vamp sections could be supplied in a white color suitable for dyeing to match the color of a particular dress.

With the construction shown in Fig. 3, the interlacing may be varied, but one form of procedure follows:

The body portion 21 is placed on top of the transverse straps 17 and with its inner edge portion 25 of the longitudinal recess directly above the forward edge of transverse strap 17. The head 26 of strips 23 and 24 is fed under strap 17 and up through opening 27, across transverse strap 28, down through opening 29, under transverse strap 30, up through opening 31, across transverse strap 32 and down through opening 35

33, which leaves the head 26 projecting about the distance shown in Fig. 1. It now remains to unlace strip 24 so that it can be cross laced into the position shown in Fig. 1. The tip end 5 34 of strip 24 may be tucked under the body portion 21 or provided with a snap (not shown) to hold it from coming undone.

Figs. 4, 5, and 6 illustrate the details of this lacing operation.

10 By interlacing the strips 23 and 24 in the manner just described, the top vamp section of the shoe which is the part most noticeable on the wearer is securely fastened in place and cannot become accidentally loosened so as to embarrass the wearer.

15 The modifications shown in Figs. 7, 8, and 9 illustrate a "pump" having a solid vamp section 40 which is suitably secured to the sole 41 of the pump. Slots 42, 43, 44, 45, 46, and 47 may 20 be die cut in the vamp to provide transverse straps 48, 49, 50, 51, and 52.

25 The removable top vamp section 53 comprises the split-tongue portions 54 and 55, each having strips 56 and 57 respectively, which may be united at their end 58.

30 The removable top vamp section 54 is assembled on the main vamp of the shoe by interlacing the tongues 54 and 55 with the transverse straps 48 to 52. The strips 56 and 57 are then unlaced and cross-woven with tongues 54 and 55 to produce the result shown in Fig. 9.

35 The modification shown in Figs. 10 and 11 provides a removable top vamp section applied to a shoe fore part vamp of the type shown in Fig. 2. The removable top vamp section shown in Figs. 10 and 11 comprises the body member 60, the inner tongue 61, and the strap 62. As shown in Fig. 11, the body portion 60 is superimposed on the transverse straps 28, 30, 32, and 63. The 40 tongue 61 is then inserted down through opening 29 under transverse strap 30, up through opening 31, across the top of transverse strap 32 and down through opening 33 and allowed to project beyond transverse strap 63. The strap 62 is now 45 passed across the top of transverse strap 30, down through opening 31, under strap 32, up through opening 33 across the top of transverse strap 63, and under the upper end 64 of tongue 61, then across the top of upper end 65 of body 50 portion 60 and down through the hole 66 therein.

55 The loop 67 in the end of strap 62 may be omitted, but if present, it is engaged by the instep strap 14.

55 My invention is capable of embodiment in different forms, all coming within the scope of the appended claims.

What I claim is:

60 1. In a shoe having a vamp or cap with transverse slits and straps formed thereby, and an overlying decorative member secured thereon by interlacing with a plurality of said straps from the rear of the vamp toward the toe portion and

by backwardly cross-lacing with one or more straps from the toe end of the vamp toward the rear of the vamp.

2. In a shoe having a vamp or cap with transverse slits and straps formed thereby, and an 5 overlying decorative member secured thereon by interlacing with a plurality of said straps from one end of the vamp toward the other end and by backwardly cross-lacing with one or more straps from the last mentioned end of the vamp 10 toward the other end of the vamp.

3. In a shoe of the type having transverse straps formed in the vamp by means of slits cut therein, the combination of a removable overlying decorative member interlaced with said straps 15 from the rear of the vamp toward the toe portion, said decorative member having an attached portion secured to it near one end of the cross straps, which portion is reversely interlaced from the toe end of the vamp toward the rear of the vamp. 20

4. In a shoe having straps forming the vamp, the combination of a removable overlying decorative member composed of two or more parallel body portions connected at one end, one or more of said body portions being interlaced with a plurality of said straps and at least one of said body portions being backwardly interlaced with one or more of said straps so that said decorative member is secured in detachable locked position. 25

5. In a shoe having straps formed in the vamp 30 by means of slits cut therein, the combination of a removable overlying decorative member composed of two or more parallel body portions connected at one end, one or more of said body portions being interlaced with a plurality of said 35 straps and at least one of said body portions being backwardly interlaced with one or more of said straps so that said decorative member is secured in detachable locked position.

6. In a shoe having straps forming the vamp, 40 the combination of a removable combination front strap and overlying decorative member composed of two or more parallel body portions connected at one end, one or more of said body portions being interlaced with a plurality of said 45 straps and at least one of said body portions being backwardly interlaced with one or more of said straps so that said decorative member is secured in detachable locked position.

7. In a shoe having straps formed in the vamp 50 by means of slits cut therein, the combination of a removable combination front strap and overlying decorative member, said decorative member being composed of two or more parallel body portions connected at the end opposite to said front strap, one or more of said portions being interlaced with a plurality of said straps formed in the vamp and at least one of said body portions being backwardly interlaced with one or more of said straps so that said decorative member is secured in detachable locked position. 55

CHARLES K. MORGAN.
